LINOLEUM OR SIMILAR ARTICLE

George V. Nobis, Readfield, Maine, and William Lynen,
Woodhaven, N. Y., assignors to Bonafide Mills, Inc.,
Lisbon, Maine, a corporation of Maine

Application February 3, 1955, Serial No. 34,346

Term of patent 7 years

(Cl. D92—17)

The drawing is a plan view of a piece of a linoleum or similar article, showing my design. On such drawing the broken lines outline a design unit which is repeated in regular succession as indicated by the extensions beyond the boundaries of such unit.

We claim:

The ornamental design for a linoleum or similar article, as shown and described.
